US00D649964S

(12) **United States Design Patent**
Chikuma et al.

(10) **Patent No.:** US D649,964 S
(45) **Date of Patent:** ** Dec. 6, 2011

(54) **PORTION OF AN ELECTRONIC COMPUTER**

(75) Inventors: **Keiji Chikuma**, Tokyo (JP); **Yuji Hirooka**, Irvine, CA (US)

(73) Assignee: **Kabushiki Kaisha Toshiba**, Minato-ku, Tokyo (JP)

(**) Term: **14 Years**

(21) Appl. No.: **29/384,004**

(22) Filed: **Jan. 25, 2011**

(30) **Foreign Application Priority Data**

Aug. 17, 2010 (JP) 2010-019872

(51) **LOC (9) Cl.** **14-02**

(52) **U.S. Cl.** **D14/315**

(58) **Field of Classification Search** ..... D14/315-327; D18/1, 2, 7, 11; 235/145 A, 145 R; 341/22, 341/23; 345/104, 156, 168, 169, 173, 87, 345/901-905; 361/679.08-679.18; 400/486-489

See application file for complete search history.

(57) **CLAIM**

The ornamental design for portion of an electronic computer, as shown and described.

DESCRIPTION

FIG. 1 is a reduced top, front and right side perspective view of portion of an electronic computer showing our new design, FIG. 2 is a perspective view showing the article in a closed position thereof,

FIG. 3 is a front elevational view thereof, FIG. 4 is a rear elevational view thereof,

FIG. 5 is a top plan view thereof,

FIG. 6 is a bottom plan view thereof,

FIG. 7 is a right side elevational view thereof,

FIG. 8 is a left side elevational view thereof,

FIG. 9 is a top plan view showing the article in the closed position thereof,

FIG. 10 is a front elevational view showing the article in the closed position thereof; and,

FIG. 11 is a right side elevational view showing the article in the closed position thereof.

Broken lines shown in the drawings illustrate portion of an electronic computer, and form no part of the claimed design.
